UNITED STATES PATENT OFFICE

DUNCAN EARL GRAHAM, OF DENVER, COLORADO, ASSIGNOR OF ONE-FOURTH TO DR. AND
MRS. GLYDE W. BUMPUS, OF DENVER, COLORADO

AUTOMOBILE TOP

Application filed October 9, 1926. Serial No. 140,523.

This invention relates to a foldable top for open automobiles, and has for its principal object the provision of a top which can be quickly and easily erected or folded by one person and which, when folded, will occupy a space no wider than the width of a single bow.

Another object of the invention is to provide a top of this character which can be but partially folded, if desired, to act as a sun shield for occupants when viewing aeronautical exhibitions, etc.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 illustrates one form of my improved top in place on a touring car.

Fig. 2 illustrates a longitudinal section through the top of Fig. 1, in the folded position. In broken line in this view one position during the folding operation is illustrated.

Fig. 3 is a longitudinal section through an alternate form of the top as designed for roadsters and the like.

Fig. 4 is a partial plan view of the top bows in the folded position.

Fig. 5 is a longitudinal section through the top of Fig. 3 in the folded position.

Fig. 6 illustrates a method which may be employed for receiving the sliding pivots employed with the top.

In Fig. 1 the automobile is illustrated at 10 and the wind-shield thereof at 11. The top material, illustrated at 27, is broken away to illustrate the supporting structure which is shown in section. The improved top is supported by means of a foldable frame comprising a main bow 12, pivoted at 13 to the automobile, immediately behind the rear door.

An angle bow 14 is pivoted at 15 in a longitudinal slot 16 in the main bow 12. Similarly

pivoted at 17 in a slot 18 in the angle bow 14, is a top bow 19. At each side of the frame a front bow supporting rod 20 is pivoted at 21 to the top bow 19 and at 22 to the angle bow 14. The front bow supporting rods 20 carry the rear extremities of a front bow 23 which is pivoted thereto at 24, the forward extremities of the supporting rods 20 being provided with rests 25 to maintain the front bow in alignment with the rods.

The front bow 23 is provided with the usual angles 26 for attachment to the posts of the wind-shield 11. The upward angle of the main bow 12 is limited by a rear curtain 28 and gypsy curtains 29 which are attached to the automobile 10.

Let us assume the top is in the position of Fig. 1 and it is desired to fold the same. The front bow 23 is detached from the wind-shield 11 allowing the main bow 12 to fall rearwardly to a substantially horizontal position, as indicated in broken line, where it is supported by any desirable top rest 30. The angle bow 14 is now forced rearwardly, causing its rear pivots 15 to slide along the slots 16 in the main bow 12, as indicated in broken line in Fig. 2, until it assumes a position within the main bow. The top bow 19 is now forced rearwardly causing its pivot 17 to slide in the slot 18 until it also lies within the main bow 12. In forcing the bow 19 within the main bow 12, the supporting rods 20, being pivoted thereto, are also brought into alignment with the main bow. The front bow 23 is now folded on its pivots 24 until it also lies within the main bow 12. In this position the entire supporting structure lies within the main bow and is of no greater width than the width of that bow.

The top covering 27 is folded between the bows, and the rear curtain 28 and gypsy curtains 29 are folded below the bows, as indicated in Fig. 2, in which position they are maintained by means of a slip cover 31.

In erecting the top, the bow 19 is drawn forwardly to its final position. This bow in unfolding will raise the angle bow 14 and bring the rods 20 to their final position. The front bow 23 is now pulled forwardly and secured to the wind-shield 11.

In the alternate forms of Figs. 3, 4 and 5, a more simplified construction is illustrated adaptable for small, one-seated automobiles of the roadster type. In this form a main bow 32 is employed arranged to be secured at 33 to the automobile. Pivoted at 34 in a slot 35 in each arm of the main bow 32 is a top bow 36. At each side of the top brace rods 37 are pivoted at 38 to the top bow 36 and at 39 to the main bow 32. A front bow 40 is pivoted to each of the brace rods 37 at 41 and maintained in alignment by means of a rest 42 carried on the extremities of the brace rods.

In folding the top from the position of Fig. 3, the front bow 40 is released from the wind-shield, indicated at 43, allowing the main bow 32 to assume a horizontal position. The top may be allowed to remain in this position to serve as a sun shield when the automobile is at rest, if desired. The top bow 36 is forced rearwardly causing its pivot 34 to travel along the slots 35. As the top bow 36 moves downwardly it will also force the brace rods 37 downwardly until they and the top bow are in alignment with the main bow. The front bow 40 is now folded within the top bow 36, as indicated at Fig. 4.

The forward extremities of the main bow 32 are bent inwardly as shown at 44 to the side of the car, thus providing a rest for the brace rods 37 which support the folded top structure. In this form, as in the previous form, the top material, indicated at 45, is folded within the bows as illustrated in Fig. 5 and maintained in place by means of a suitable slip cover 46. It is necessary for the top bow 36 to fold over the pivot 39 in the main bow, and it is therefore off-set as indicated at 47 to receive the pivot.

In the drawings I have illustrated the slots for the sliding pivots as formed directly in the material. They may be thus formed if the bows are made of flat metal stock. For wooden bows and the like the slots may be carried as illustrated in Fig. 6, that is, a flat metal strip 49 may be secured to the bow, illustrated at 48, by means of rivets 50. A slot 51 is formed in the strip 49 for the reception of the sliding pivot.

While a specific form of the improvement has been described and illustrated herein, it is desired to be understood that the same may be varied, within the scope of the appended claims, without departing from the spirit of the invention.

Having thus described the invention, what I claim and desire to secure by Letters Patent is:

1. A foldable frame for supporting a flexible automobile top comprising a main bow; a forwardly extending top bow pivoted to the inside of said main bow and a foldable front bow pivoted to the inside of both said main bow and said top bow, said main bow

being mounted to incline rearwardly and the remaining bows to incline forwardly when the top is erected, and all of said bows being constructed and shaped to interfit and adapted to lie in the same plane when folded.

2. A foldable frame for supporting a flexible automobile top comprising a main bow; a forwardly extending top bow pivoted to the inside of said main bow and a foldable front bow pivoted to the inside of both said main bow and said top bow, each of the pivot points being placed in the plane of the bow which carries it and all of said pivots adapted to lie within said main bow when said frame is folded and said front bow being constructed to fit within the top bow and said top bow being constructed to fit within the main bow and clear the pivots thereon so that all of said bows lie in the same plane when folded.

3. A foldable frame for supporting a flexible automobile top comprising a main bow; a top bow pivoted at each of its extremities to the inside of and on the center line of said main bow; front supporting bars pivoted to the inside of and on the center lines of both said main bow and said top bow; and a front bow pivoted at its extremities on the inside faces of said supporting bar and along the center line of the latter foldable to lie in a plane and be encompassed by said intermediate bow, said top bow being constructed and shaped to clear the pivot on the main bow so that the top and front bows will lie in the plane of said main bow when folded.

4. A foldable frame for supporting a flexible automobile top comprising a main bow; a top bow pivoted at each of its extremities to the inside of and on the center line of said main bow; front supporting bars pivoted to the inside of and on the center lines of both said main bow and said top bow; and a front bow pivoted at its extremities on the inside faces of said supporting bar and along the center line of the latter, the length of the arms of the top bow being less than the distance from their pivots to the top of the main bow and said arms being shaped to clear the pivots thereon so that said top bow may pass within said main bow to lie in a plane with and be entirely encompassed thereby.

5. A foldable frame for supporting a flexible automobile top comprising a main bow; a top bow pivoted at each of its extremities to the inside of and on the center line of said main bow; front supporting bars pivoted to the inside of and on the center lines of both said main bow and said top bow; and a front bow pivoted at its extremities on the inside faces of said supporting bar and along the center line of the latter, the length of the arms of the top bow being less than the distance from their pivots to the top of the main bow so that said top bow may pass within said main bow, the length of the arms of the front

bow being less than the folded distance between the top of the top bow and the pivots between the said front bow and said supporting rods so that said front bow will fold 5 within the plane of said top bow.

6. A foldable frame for supporting a flexible automobile top comprising a main bow; a top bow pivoted at each of its extremities to the inside of and on the center line of said 10 main bow; front supporting bars pivoted to the inside of and on the center lines of both said main bow and said top bow; and a front bow pivoted at its extremities on the inside faces of said supporting bar and along the center 15 line of the latter, the width between the arms of the top bow being less than the width of the main bow; the spacing between the supporting bars being less than the width of the top bow and the width between the arms of 20 the front bow being less than the spacing of said supporting bars so that said front bow can pass between said supporting bars, said supporting bars between the arms of said top bow, and said top bow into said main bow so 25 that the several bows lie in the same plane.

7. A foldable automobile top having a supporting frame comprising a supporting bow, an intermediate bow slidably and pivotally mounted on the inside and in the transverse 30 plane of said supporting bow, and a foldable front bow pivotally connected with said supporting bow and said intermediate bow at fixed points and constructed and shaped to interfit with and adapted to be folded inside 35 the intermediate bow when the top is folded.

8. A foldable automobile top having a supporting frame comprising a supporting bow mounted for swinging movement and provided with elongated slots on the inner sides 40 of the side arms, an intermediate bow having pivotal bearings slidably mounted in said slots within the transverse plane of said supporting bow, and a front bow pivotally connected at its ends with the supporting bow 45 within the transverse plane thereof and above said slots and having cross pivotal connection with the intermediate bow at points on each side spaced from the pivotal mounting of said bows.

50 9. A foldable automobile top having a supporting frame, comprising a supporting bow rearwardly inclined when in use and having elongated slots at the middle portion on the inner side of each of the side arms thereof, an intermediate bow having its ends pivotally and freely slidably mounted in said slots to slide in the transverse plane of said supporting bow, front bow brace and supporting rods pivotally connected with said supporting bow on the inner sides of the arms thereof at points above the slots and pivotally cross connected with the side arms of said intermediate bow, and a front bow foldably mounted at the free ends of the front bow brace and supporting rods, all of said por-

tions of the supporting frame being adapted to lie in the transverse plane of said supporting bow when folded.

10. A foldable frame for supporting a flexible automobile top comprising a main bow 70 pivotally mounted on an automobile body to incline rearwardly, a top supporting bow pivotally connected midway on the inner sides of the arms of said main bow and having said pivotal connections movable endwise 75 with respect to said arms, and a front supporting bow having the extremity of its arms pivotally connected on the inner sides of said main bow arms and having cross pivotal connection with said top supporting bow, said 80 top and front supporting bows being so formed and constructed and the pivotal connections being so made that said top bow will fold within the main bow and said front bow will fold within the top bow to thus dispose 85 the several bows in a single plane when folded.

In testimony whereof, I affix my signature.
DUNCAN EARL GRAHAM.
